UNITED STATES PATENT OFFICE.

CHARLES H. SMITH, OF BIRMINGHAM, ALABAMA, ASSIGNOR TO THE SMITH SAFETY COUPLER COMPANY, OF MEMPHIS, TENNESSEE.

CAR-COUPLING.

SPECIFICATION forming part of Letters Patent No. 560,439, dated May 19, 1896.

Application filed August 6, 1895. Serial No. 558,420. (No model.)

To all whom it may concern:

Be it known that I, CHARLES H. SMITH, of Birmingham, in the county of Jefferson and State of Alabama, have invented new and useful Improvements in Car-Couplings, of which the following is a full, clear, and exact description.

My invention relates to improvements in car-couplings of the Janney type, and has for its object to provide additional features of improvement for the car-couplings for which Letters Patent of the United States were granted to me on March 19, 1895, No. 536,052, which improvements will simplify the construction of said patented coupling and render the same more effective in service.

To these ends my invention consists in the peculiar construction and combination of parts, as is hereinafter described, and indicated in the claims.

Reference is to be had to the accompanying drawings, forming a part of this specification, in which similar characters of reference indicate corresponding parts in all the views.

Figure 1 is a partly-sectional plan view of the improvements substantially on the line 1 1 in Fig. 3. Fig. 2 is a transverse sectional view essentially on the line 2 2 in Fig. 1. Fig. 3 is a longitudinal sectional view substantially on the line 3 3 in Fig. 1. Fig. 4 is a longitudinal sectional view of the improved coupling, showing parts of the same in relative positions for connecting with each other; and Fig. 5 is a sectional plan view of the detached knuckle 13 of the car-coupling, showing a feature of improvement thereon.

The car-coupling shown and described in the said Letters Patent No. 536,052 will first be briefly described, and afterward the present improvements will be located therein and fully explained.

A draw-head 10 is formed on an integral draw-bar 11, preferably by casting said parts together, the draw-head being widened and chambered, as at 12, for the reception of the knuckle 13, that is substantially L-shaped, having a lateral limb 13^a and a rearwardly-extending tailpiece 13^b. The knuckle is pivoted at the front of the draw-head between the parallel upper and lower ears 10^a, so that the tailpiece 13^b may have one side edge of

the same in contact with a side wall of the draw-head chamber and enter an ear 13^d, formed on the rear of the tailpiece within a lateral recess 10^b in the said wall, as shown in Fig. 1, the latch jaw or link 13^a then projecting toward the other side of the draw-head. A horn 10^d is formed on the draw-head and is concaved on its front wall to facilitate the coupled engagement with the latch-jaw 13^a of a knuckle on a similar coupling, and the horn is cast hollow to lighten it, its inner wall extending longitudinally rearward in alinement with a similar wall of the draw-bar 11. A box-like formation 10^e is produced on the upper portion of the draw-head 10, having a cavity 12^a, that is an extension of the cavity 12, the rear wall of said portion 10^e being substantially vertical and its forward wall indented to produce a concave recess 12^b, as shown in Fig. 3, and this is one feature of the improvement. The cavity 12 in its rearward portion has opposite channels 12^c formed in its side walls, which loosely receive transverse trunnions 14^b, formed on the rear end of the limb 14^a, which projects rearwardly from the gravity-block 14. The gravity-block 14 is substantially L-shaped, having an upwardly-extending member whereon two spaced hooks 14^c are formed and which bend forwardly and downwardly. The gravity-block has such a proportionate width as will permit it to rock between the straight inner wall of the horn 10^d and a side edge of the tailpiece 13^b when the latter is adjusted to enter its ear 13^d in the recess 10^b of the draw-head side wall, and it will be seen that when said parts are adjusted, as indicated in Fig. 1, the gravity-block 14 serves to hold the tailpiece from swinging and retains the latch-jaw 13^a projected toward the horn 10^d.

A lifting-bar 15 is provided, which is by its improved construction curved edgewise a suitable degree, and on the upper end of the lifting-bar an integral cap-piece 15^a is formed, which is a feature of improvement. The lifting-bar 15 is furnished at its lower end with two opposite lugs 15^b, that are curved on their upper sides so as to engage with the spaced hooks 14^c and adapt the bar for lifting the gravity-block. The length of the lifting-bar 15 is such as will allow the gravity-block

14 to rest on the bottom of the cavity 12, when the cap-piece 15^a is seated over the opening produced at the top of the box portion 10^e by the extension of the cavity 12^a through 5 said upper part of the draw-head body, and the shape and size of the cap-piece permits it to seal the opening mentioned when the block 14 is completely lowered, as shown in Fig. 3.

By the formation of the cap-piece 15^a integral with the lifting-bar 15 the cost of the latter is considerably reduced and the construction of the car-coupling correspondingly simplified, and as such a formation of parts requires that provision be made for connecting the lugs 15^b with the hook 14^c the concave recess 12^b is produced in the front wall of the part 10^e, which will enable the ready introduction of the lugs below the hooks, if the block 14 is elevated and the lifting-bar is 20 introduced, as clearly shown in Fig. 4.

A rock-shaft 16 is transversely and loosely supported on the end wall A of the car, and on said shaft, directly above the car-coupling, a rock-arm 17 is mounted and affixed, so that 25 the free end of the rock-arm may be loosely connected by links 18 or other means with the cap-piece 15^a of the lifting-bar 15, whereby a partial rotation of the rock-shaft by an attached crank-handle 19 will elevate the 30 gravity-block 14, as indicated by dotted lines in Fig. 3. The tailpiece 13^b is sloped on its upper face from near the pivot-bolt 13^c of the knuckle to the ear of said tailpiece, which will permit the tailpiece to swing below the 35 gravity-block 14 and the latter to rest on the ear when the knuckle is in open adjustment, as shown in dotted lines in Fig. 1, and an ear 14^d is formed on the front of the gravity-block at its lower edge to aid such an engagement of parts. It has been found of advantage to provide means for automatically 40 swinging the tailpiece toward the side wall of the horn 10^a when the rock-shaft 16 is manipulated to lift the block 14, and to this end 45 a plate-spring 20 is furnished, which is another feature of improvement. The spring 20 has a lateral toe *a* turned at an angle from its body at one end of the same, and the body is bent to curve it, as shown in Fig. 5. An 50 elongated recess *b* is produced in the edge of the tailpiece 13^b of the knuckle 13, which in service is nearest to the side wall of the draw-head having the recess 10^b, and said recess near the perforation for the pivot-bolt of the 55 knuckle is deepened to produce a pocket for the reception of the toe *a* of the spring 20. A preferably integral keeper-bar *c* is formed transversely of the recess *b* near the joint perforation of the knuckle, and below said 60 bar the elongated recess that is bridged thereby has a depression formed in its bottom, as clearly shown in Fig. 5.

It will be seen that by the described construction of parts the curved plate-spring 20 65 may be securely connected with the tailpiece 13^b by introducing the end of the spring having the toe *a* below the bar *c* and pushing the

spring toward the pocket at the end of the recess *b*, so that the toe will spring into the pocket and the plate-spring be retained in position over the recess by means of the keeper-bar, as is plainly indicated in Fig. 5.

When two cars having the improved couplings are to be coupled together, it is only necessary to push said cars toward each other, 70 if the knuckles of the couplings are adjusted, as indicated by dotted lines in Fig. 1, as the impinge of the latch-jaw 13^a of one knuckle 13 on the tailpiece of the other knuckle will instantly swing both of the knuckles into 80 coupled engagement in an obvious manner, the gravity-blocks 14 dropping into locking position when the tailpieces of the knuckles have assumed the position shown by full lines in Fig. 1. In case one knuckle of two approaching draw-heads is in locked condition 85 and the other one in opened adjustment, the coupling of the draw-heads may be produced by the impact of the latch-jaw of the closed coupling on the tailpiece of the open coupling, as will be readily understood; and should 90 both the car-couplings have their knuckles in locked condition one must be released to permit a coupled connection to be effected, which release may be safely effected by manipulating the crank-handle 19, which effects the elevation of the block 14 and permits the spring 20 to throw the tailpiece around under the gravity-block.

It will be seen that the details of construction constituting the features of additional improvement add to the efficiency of the coupling shown and described in my aforesaid Letters Patent No. 536,052, and also cheapen the production of said car-coupling.

Having thus described my invention, I claim as new and desire to secure by Letters Patent—

1. In a car-coupling, the combination with a chambered draw-head having an upward extension of said chamber and a concave depression in the front wall of the said upward chamber extension, of a pivoted spring-actuated knuckle, a pivoted gravity-block provided with hooks on its upper end, the said gravity-block being adapted to hold the knuckle in the closed position, and a curved lifting-bar having lugs on its lower end adapted to engage the said hooks on the gravity-block, substantially as described.

2. In a car-coupling of the Janney type, the combination with the knuckle having an edge wall of its tailpiece longitudinally recessed, the said recess having a pocket at its end nearest the knuckle-pivot, and a keeper-bar across the recess, of a curved plate-spring having a toe and interlocked with the pocket and keeper-bar and normally projecting the free end of the spring away from the tailpiece of the knuckle, substantially as described.

3. In a car-coupling, the combination with a chambered draw-head having an upward extension of said chamber, and a concave depression in the front wall of said upward

chamber extension, of a pivoted gravity-block, and a curved lifting-bar, having an enlarged cap-piece on its upper end and two opposite lugs on its lower end, said lower end being adapted to enter the chamber extension and engage its lugs with hooks on the upper end of the gravity-block, when said block is elevated and the lower end of the lifting-bar oc-

cupies the concave depression in the wall of the chamber extension, substantially as described.

CHARLES H. SMITH.
